UNITED STATES PATENT OFFICE.

FORREST E. RICKETTS, OF BALTIMORE, MARYLAND.

ARC-EXTINGUISHER.

1,308,257.

Specification of Letters Patent.

Patented July 1, 1919.

Application filed March 13, 1916. Serial No. 83,786.

To all whom it may concern:

Be it known that I, FORREST E. RICKETTS, a citizen of the United States, and a resident of Baltimore, in the State of Maryland, **5** have invented a new and useful Improvement in Arc-Extinguishers, of which the following is a specification.

My invention relates to electrical systems of distribution and particularly to **10** apparatus for extinguishing arcs that occur in such systems without disturbing the operation of the apparatus connected thereto.

One object of my invention is to provide a device of the above indicated character **15** that shall so alternately open and close a circuit interrupter to reduce the voltage of the circuit that the arc will be extinguished without causing the apparatus connected to the circuit to fall out of synchronism.

20 Another object of my invention is to provide a device of the above indicated character that shall have means for preventing the automatic opening and closing of the interrupter if the arc is not extinguished within a predetermined time.

My copending application, Serial No. 735,376, filed December 7, 1912, discloses a device for reducing and restoring the voltage of a generator to extinguish an arc. The **25** device operates upon the principle that an arc will break within a fraction of a second after the voltage has been reduced substantially to zero. While a device of this type operates satisfactorily in a distributing system as a whole, it does not provide means for independently extinguishing the arcs in the feeder circuits. In my present invention, I provide a circuit interrupter that is adapted to be opened when a short circuit **30** or an arc occurs, and I further provide means for reclosing the interrupter in accordance with the difference in voltage between the respective sides of the interrupter. Since some short circuits are of a permanent **35** nature and are not maintained by an arc, I provide means to prevent the continued automatic opening and closing of the interrupter if the short circuit persists for a predetermined time. It has been found that this **40** time should be such that an ordinary arc would be extinguished if the interrupter were permitted to alternately open and close a predetermined number of times.

The single figure of the accompanying **45** drawing is a diagrammatic view of a distributing system that is provided with an

arc-extinguishing means embodying my invention.

A generator 1 supplies energy to the main conductors 2, 3 and 4 of a distributing system 5. A feeder circuit 6, comprising conductors 7, 8 and 9, is operatively connected between the main distributing circuit 5 and a load 10, such as a motor or other similar device. The feeder circuit 6 is provided **60** with a circuit interrupter 11 and with series transformers 12, 13 and 14 that are connected to its respective conductors.

The circuit interrupter 11 is provided with a closing electromagnet 15 and a tripping **70** electromagnet 16. The secondary windings of the transformers 12, 13 and 14 are operatively connected to windings 17 and 18 of overload relays 19 and 20 that are provided with movable contact members 21 and **75** 22. The movable contact members 21 and 22 are adapted to engage stationary contact members 23 and 24 when a short circuit occurs on the feeder circuit 6. The contact members 23 and 24 are connected in parallel **80** between one terminal of the winding of the electromagnet 16 and one terminal 25 of an electromotive force generator 26. The other terminal of the electromagnet 16 is connected to the other terminal 27 of the electromotive force generator 26. Thus, the circuit breaker 11 is adapted to be tripped when **85** a short circuit occurs across any of the conductors of the feeder circuit 6.

The primary winding of a transformer 28 **90** is connected across the conductors 3 and 4 of the main circuit 5, and the primary winding of a similar transformer 29 is connected across the corresponding conductors 7 and 8 of the feeder circuit 6. Thus, the primary **95** windings of the transformers 28 and 29 are, in reality, connected to the same conductors but are separated by the circuit interrupter 11. The secondary windings of the transformers 28 and 29 are so connected to two **100** conductors 30 and 31 that, when the circuit interrupter 11 is closed, one of the windings neutralizes the effect of the other, and no current traverses the conductors 30 and 31. However, when the circuit interrupter 11 is tripped, the voltage of the transformer 29 will be substantially zero while the voltage of the transformer 28 will be substantially normal. Hence, voltage **105** proportional to the normal voltage of the circuit will be impressed across the conductors 30 and 31.

The conductor 30 is connected to one stationary contact terminal 32 of a double-pole single-throw switch 33. The corresponding stationary contact terminal 34 of the switch 33 is connected, through a conductor 35, to one terminal of the winding of the electromagnet 15 the other terminal of which is connected to the terminal 27 of the generator 26. The conductor 35 is also connected to 10 the stationary contact terminal 36 of a single-pole double-throw switch 37 the other stationary contact terminal 38 of which is connected, through a conductor 39, to one terminal of the winding of the electromagnet 15 16. The movable contact member 40 of the switch 37 is connected to the terminal 25 of the generator 26. The movable contact member 41 of the switch 33 is connected to a stationary contact member 42 of a relay 20 43, and the remaining movable contact member 44 of the switch 33 is connected, through a conductor 45, to one terminal of the winding 46 of a relay 47 and to one terminal of the winding 48 of a definite time-limit relay 49. The conductor 31 is connected to the other terminal of the winding 46 and also to the other terminal of the winding 48 of the relay 49. The other stationary contact member 50 of the relay 43 is 25 connected to the terminal 25 of the source 26. One terminal of the winding 51 of the relay 43 is connected to the stationary contact member 50, and the other terminal of the winding 51 is connected to the stationary contact member 52 of the relay 47. The other stationary contact member 53 of the relay 47 is connected, through a conductor 54, to the terminal 27 of the generator 26. The winding 51 of the relay 43 is 30 adapted to actuate a movable bridging contact member 55 to engage the stationary contact members 42 and 50, and the winding 46 of the relay 47 is adapted to actuate a movable bridging contact member 56 to 35 engage the stationary contact members 52 and 53.

The relay 49 may be constructed as set forth in application, Serial No. 771,888, filed by A. W. Copley and B. H. Smith and 50 assigned to the Westinghouse Electric and Manufacturing Company, and comprises a main winding 48, an auxiliary winding 57 and secondary windings 58. A normally saturated transformer 59 is operatively connected between the windings 57 and 58 in order to cause the armature 60 to rotate at a constant speed irrespective of the energy traversing the winding 48. The armature 60 is mounted on a shaft 61 upon which a 55 movable contact member 62 is also mounted. The movable contact member 62 is adapted to engage a stationary contact member 63 a predetermined time after the winding 48 is energized. The contact members 62 and 60 65 63 constitute the separable terminals of a

winding 64 that is adapted to so coöperate with the movable member of the relay 47 that, when the winding 64 is short circuited, the movable contact member 56 will not engage the stationary contact members 52 70 and 53.

When a short circuit, such as an arc, occurs on the feeder circuit 6, sufficient energy 75 will traverse the windings of the transformers 12, 13 and 14 to cause the movable contact members 21 and 22 of the relays 19 and 20 to engage their respective stationary contact members 23 and 24 to complete a circuit from one terminal of the generator 26 through the electromagnet 16 to cause the 80 circuit interrupter 11 to be tripped. When the circuit interrupter 11 is tripped, sufficient voltage will be impressed across the conductors 30 and 31 to cause the relay 47 85 to operate. The operation of the relay 47 will effect engagement between its movable contact member 56 and its stationary contact members 52 and 53, and the relay 43 will operate to effect engagement between its stationary contact members 42 and 50 and its 90 movable contact member 55. When the movable contact member 55 engages the stationary contact members 42 and 50, a circuit will be completed from one terminal of the generator 26 through the stationary contact member 34 and the movable contact member 41 of the switch 33, the conductor 35 and the electromagnet 15 to the other terminal of the generator 26. Thus, the electromagnet 15 will be energized to close the circuit 95 interrupter 11. Since the time between the opening and closing of the circuit interrupter 11 is relatively short, the motor 10 will not drop out of synchronism, but any arc across the conductors of the feeder circuit 105 6 will be extinguished. However, if the arc persists after the circuit interrupter 11 is closed, the relays 19 and 20 will again operate to so energize the electromagnet 16 as to trip the circuit interrupter 11, and, when 110 the interrupter 11 is again tripped, the transformers 28 and 29 will again effect the operation of the relays 47 and 43 to immediately close it.

It has been determined that, if the short 115 circuit is caused by a non-permanent arc, it will be extinguished by reducing the voltage to substantially zero a number of times. However, if the short circuit is permanent in nature, it is advisable to prevent the 120 automatic alternate opening and closing of the circuit interrupter after the expiration of a time period during which the circuit interrupter has opened and closed a predetermined number of times. Thus, the first 125 time that the circuit interrupter 11 is interrupted, the winding 48 of the relay 49 will be energized and its armature 60 will start to operate, and, after a predetermined time interval, the contact member 62 will engage 130

the contact member 63 to short circuit the winding 64 of the relay 47 and thus render the relay 47 inoperative. Consequently, the circuit interrupter 11 will remain open so long as the winding 64 of the relay 47 remains short circuited. The relay 47 will thus remain inoperative until the voltage across the winding 48 or the winding 46 has been reduced to zero for a sufficient time period to return the movable contact member 56 to its original position. This may be accomplished after the trouble on the feeder circuit 6 has been cleared by opening the switch 33 and closing the circuit interrupter 11 by moving the movable contact member 40 of the switch 37 into engagement with its stationary contact terminal 56. Thus, the motor 10 may be disconnected from the main circuit 5 when a permanent short circuit occurs thereon, and when this short circuit has been removed and the circuit interrupter 11 is again closed, the arc-extinguishing device is in such a position that it may again operate immediately. Similarly, if the arc should be extinguished before the contact member 62 engages the stationary contact member 63 of the relay 49, the circuit interrupter 11 will be closed, the motor 10 will continue to operate and the relays will be in such position as to be operative whenever another short circuit occurs.

I do not limit my invention to the particular devices shown, as many modifications may be made therein without departing from the spirit and scope of my invention as set forth in the appended claims.

I claim as my invention:

1. In a system of distribution, the combination with a circuit interrupter and means for opening it when an arc obtains on the system, of a relay so connected to the circuit that, when a difference in potential obtains across the interrupter, it will cause the interrupter to be reclosed, and means for so controlling the operation of said relay that the interrupter will be precluded from reclosing after the arc has persisted for a predetermined period of time.

2. In a system of distribution, the combination with a circuit interrupter and means for opening it when an arc obtains on the system, of a relay so connected across the interrupter that, when a difference in potential obtains thereacross, the interrupter will be reclosed, and means for so controlling the operation of said relay that the interrupter will be precluded from reclosing when the arc persists for a predetermined period of time.

3. In a system of distribution, the combination with a circuit interrupter and means for opening it when an arc obtains on the system, of a relay so connected across the interrupter that, when a difference in potential obtains thereacross, the interrupter

will be reclosed, and a time-element device for so controlling the operation of the relay that the interrupter will be precluded from reclosing when the arc persists for a predetermined period of time.

70

4. In a system of distribution, the combination with a circuit interrupter, of means for tripping the circuit interrupter when an arc obtains on the system, and means dependent upon the difference in voltage between the terminals of the circuit interrupter for automatically closing the same.

75

5. In a system of distribution, the combination with means for disconnecting a portion of the system when an arc obtains thereon, of means dependent upon a difference in voltage between the two portions of the system for reconnecting the same.

80

6. In a system of distribution, the combination with means for automatically reducing the voltage of the system and for restoring its voltage before the apparatus connected thereto falls out of synchronism, of a time-limit relay for preventing the restoration of the voltage after it has been alternately reduced and restored for a predetermined time period.

85

7. In a system of distribution, the combination with means for automatically disconnecting a portion of the system when an arc obtains thereon and for reconnecting the same before the apparatus connected thereto falls out of synchronism, of means for preventing the reconnection after the arc has existed a predetermined time period.

90

8. In an alternating-current system of distribution, the combination with a feeder circuit and a circuit interrupter therefor, of means for tripping the interrupter when an arc obtains on the feeder circuit, means dependent upon the difference in voltage between the terminals of the interrupter for closing it, and a relay adapted to render the reclosing means inoperative a predetermined time period after the arc obtains.

100

9. In a system of distribution, the combination with a circuit interrupter and means for opening it when an arc obtains on the system, of a relay for reclosing the interrupter, transformers so connected to both terminals of the interrupter that, when it is tripped, sufficient energy will be supplied to the relay to reclose the interrupter, and a time-limit relay adapted to prevent the reclosure of the circuit interrupter when the arc persists for a predetermined time period.

110

10. In a system of distribution, the combination with a circuit interrupter and means for tripping it when an arc obtains on the system, of a relay for reclosing the interrupter, transformers so connected to the terminals of the interrupter that, when it is tripped, sufficient energy will be supplied to the relay to reclose the interrupter,

115

120

125

130

a definite time-limit relay adapted to prevent the automatic reclosure of the circuit interrupter when the arc persists for a predetermined time period, and means for normally reclosing the circuit interrupter.

- 5 11. In a system of distribution, the combination with a circuit interrupter, of means for tripping the interrupter when an arc obtains on the system, automatic means dependent upon a difference in voltage across the interrupter for reclosing the interrupter, and means for preventing the reclosure of the interrupter when the arc persists for a pre-determined period of time.
- 10 12. In a system of distribution, the combination with a circuit interrupter and

means for opening it when an arc obtains on the system, of means for reclosing the interrupter, means so connected to the terminals of the interrupter that, when it is 20 opened, sufficient energy will be supplied to the reclosing means to reclose the interrupter, and a definite time-limit relay for so controlling the reclosing means that the interrupter is prevented from reclosing when 25 the arc persists for a predetermined period of time.

In testimony whereof, I have hereunto subscribed my name this 8th day of March 1916.

FORREST E. RICKETTS.
